SPECTACLE CLEANING TISSUE BOOKLET

Herald T. Snyder, Seattle, Wash., assignor to
Tom W. Holman, as trustee

Application May 29, 1941, Serial No. 395,816

1 Claim. (Cl. 206—57)

My invention relates to a spectacle cleaning tissue containing booklet or pad. More particularly, my invention relates to a booklet containing a plurality of spectacle cleaning tissues in superposed relation in a booklet of a construction that a tissue is readily available for cleaning spectacles.

A common practice for parties who wear spectacles is to carry cleaning cloths, as handkerchiefs or the like. However, such prior practice has a serious disadvantage in that the fuzz from the cloth tends to adhere to the spectacles—thus rendering cleaning difficult or impossible.

Furthermore, the use of cleaning cloths inherently provides for a cloth that is carried in a pocket or in a purse and which picks up the dirt or small particles which may be in one's pocket or in one's purse.

Furthermore, the use of cleaning cloths has a tendency to rub against a lens particles, such as hard gritty particles, which are often present in one's pocket or purse. These particles tend to scratch the lens and otherwise render the spectacles unfit for use.

Optical stores have generally recognized the desirability of cleaning tissues for use in cleaning spectacles as distinguished from a cloth. In other words, it has been demonstrated that if the cleaning tissue may be used only once and a clean surface presented for such use that the most complete cleaning of the spectacles or glasses is obtained.

It is an object of my invention to provide a booklet of a size which will contain tissues of a convenient size so that a plurality of tissues may be carried by a person so that spectacles may be cleaned when desired.

It is a further object of the invention to provide a tissue folded in a form so that a clean surface is available for cleaning the spectacles.

It is a further object of the invention to provide a tissue containing booklet so that the tissues are arranged in a pack in superposed relation so that one of the tissues may be made readily available for use by merely blowing against the top tissue of the pack.

It is a further object of the invention to provide a tissue in a form where the top member may be made available by blowing so that the blowing will function for two purposes, viz., to unfold the top tissue and make the same readily available and second to remove any "paper dust" which may adhere to the tissues from the manufacturing process.

It is a further object of the invention to pro-

vide a booklet in a form which has a sealing means so that the booklet may be locked closed or readily opened, and this in an economical form.

5 The above mentioned general objects of my invention, together with others inherent in the same are attained by the device illustrated in the following drawing, the same being a preferred exemplary form of embodiment of my invention, throughout which drawing like reference numerals indicate like parts:

Figure 1 is a perspective view of a booklet embodying my invention with the cover of the booklet locked in closed position;

15 Fig. 2 is a perspective view with the top cover member open and showing by arrows the direction of the air to open the tissues;

Fig. 3 is a perspective view showing the top sheet of the cleaning tissue blown to unfolded position;

20 Fig. 4 is an end view showing the off-set relation between the notches in the top and bottom cover members;

Fig. 5 is a view similar to Fig. 4 showing the 25 top and bottom cover members in interlocked position, similar to the position shown in Figure 1; and

Fig. 6 is a fragmentary view showing the folding arrangement of the tissues in the booklet.

30 Top and bottom cover members 10 and 11 are provided with a plurality of cleaning tissues therebetween. The cleaning tissues comprise the bottom fold 12 and the shorter top fold 13. Said tissues are provided with the free end of the bottom fold 12 secured between the bottom cover member 11 and the top cover member 10. Staples 16 secure the cover members and the free ends of the bottom folds of the various cleaning tissues in booklet form.

40 Referring more particularly to Figs. 4 and 5 a notch 14 is provided in the top cover member 10 and a notch 15 is provided in the bottom cover member 11. The notches 14 and 15 are in off-set relation so that when the booklet is unlocked 45 the notches 14 and 15 will be as they appear in Fig. 4. By twisting the bottom cover member 11 and the top cover member 10 at the juncture of said notches, the off-set relation of the notches 14 and 15 will serve to provide a locking device 50 for the device so that the edges will appear as shown in Figure 1 or Fig. 5.

A top fold 13 of each tissue is shorter than the bottom fold 12. This provides for the top fold 13 being in spaced relation to the staples 16 and being free therefrom. By such provision one

may blow in the direction of the arrows 17 in Fig. 2 and the top fold 13 of the cleaning tissue will assume the position shown in Fig. 3. By blowing to open up or unfold a tissue, I am able to accomplish two purposes. First the type of tissue which is most desirable for use in cleaning glasses or spectacles has a tendency for the two surfaces to adhere together. By my invention one is able to open a tissue readily, by blowing, which will thus serve to open a tissue and at the same time tend to blow off any "paper dust" which is present by reason of the manufacturing process of paper. In the cleaning of spectacles it is to be remembered that normally a person places the cleaning tissue between the thumb and the next finger and by a rubbing, rotating action the spectacles are cleaned. In other words, the portion of the cleaning tissue that is used in each cleaning operation is relatively small. Therefore, there is a great wastage unless the cleaning tissues are of a size which will be used in one operation. Also the size of the booklet containing the cleaning tissues should be such as to permit convenient carrying in one's pocket or purse so that the device will not become lost, or misplaced. With such conditions in mind I have found that the booklet may have a size such as one and three-quarters inches by three and one-quarter inches and meet the convenience of the user and without wastage of paper.

The booklet of my invention containing cleaning tissues may be economically manufactured and without requiring special tools or devices therefor.

The top cover member 10, and the bottom cover member 11 may be made of any suitable heavy paper to serve as covers. Also the staples 16 may be any of the usual staples, as the common metal staples used for fastening a plurality of sheets of paper together. The tissues 12-13 may be any of the commercially available cleaning tissues which are sold under any trade-names as "Kleenex." The fold 12 of the cleaning tissue is longer than the fold 13 so that the shorter fold 13, which is the top fold, will not be fastened and may be unfolded by blowing, as indicated by the arrows 17 in Fig. 2 of the drawing.

The front and back cover members 10 and 11

will well serve as carriers of advertising medium so that a method of merchandizing devices embodying my invention is to permit the advertiser to pay for the booklet and distribute the booklet free, similar to the present day method of distributing booklets of matches.

In my invention I have thus provided for a cleaning tissue of a size which is suitable for one cleaning operation of the glasses. Furthermore 10 I have provided a tissue which has one fold to keep the cleaning surface clean and which may be readily unfolded, as by blowing, and a clean surface will be presented for each cleaning operation, even though the user may carry the booklet 15 in his pocket or her pocketbook and the dirt, dust or grit which is often there present will not affect the cleaning tissue or soil the surface which is to be used in the cleaning operation. I have also provided for using the same act of 20 blowing to remove "paper dust" which may be present in the tissue because of the manufacture thereof.

Furthermore, I have provided an economical locking device by reason of the two off-set notches 25 14 and 15.

Obviously, changes may be made in the form, dimensions and arrangements of the parts of my invention without departing from the principle thereof, the above setting forth only a preferred 30 form of embodiment.

I claim:

A spectacle cleaning tissue booklet comprising a bottom cover member; a plurality of cleaning tissues in superposed relation and of a length less than said cover member; a top cover member matching said bottom cover member; staple devices extending through said bottom cover member, the said tissues, and said top cover member; and a locking means in the free ends of said top and bottom cover members comprising a notch member in said top member and a parallel closely adjacent and off-set notch in said bottom member, said off-set notches movable into and out of interlocking relation and when in interlocked relation held there by the resistance to lateral displacement of said cover members.

HERALD T. SNYDER.
